VEHICLE HORN

Joseph E. Griffin, Savannah, Ga.

Application August 29, 1932, Serial No. 630,918

4 Claims. (Cl. 177—7)

My invention relates to vehicle horns and more particularly to that type wherein a disk of recorded sound is employed to produce a signal warning, and it consists in the constructions, arrangements and combinations herein described and claimed.

It is an important object of my invention to provide a motor driven horn wherein the sound record is automatically brought into and out of engagement with a stylus, upon energization of the motor.

It is also an object of my invention to provide means for accurately positioning the stylus upon the record disk, as well as eliminating undesired vibrations to the diaphragm of the horn.

It is a still further object of the invention to provide a structure wherein the record disk may be readily removed from its supporting head whereby disks having various sound records or "slogans" may be interchanged.

Additional objects, advantages and features of invention will be apparent from the following description, considered in conjunction with the accompanying drawing, wherein:

Figure 1 is a sectional view through a horn constructed in accordance with my invention, illustrating the parts in operative position;

Fig. 2 is a similar view on a reduced scale, illustrating the parts in inoperative position;

Fig. 3 is an enlarged vertical sectional view illustrating the record disk supporting and securing means;

Fig. 4 is a cross section on the line 4—4 of Fig. 3; and

Fig. 5 is a plan view of the combined centering and fastening means for the record disk.

In carrying out my invention I provide a horn which, in the present instance, comprises a casing 11 flanged at 12 for attachment to a diaphragm casing. The diaphragm casing comprises two sections 14 and 15, respectively, and between these sections is secured a diaphragm 16. The latter, as will be observed, is fluted or corrugated for a purpose hereinafter explained. The section 14 is provided with a central opening 17 through which a stylus 18 carried by the central portion of the diaphragm 16 is projected while the section 15 is provided with the usual funnel-shaped horn member 19 for permitting egress of sound. The opening 17 at its lower point has a bearing 20 forming a rocking pivot for the stylus as will now be described.

The stylus 18 is secured centrally of the diaphragm but the stylus point 21 is offset by virtue of the angularly disposed intermediate portion

22. The portion 22 is so disposed as to overlie and contact with the pivot 20 as clearly shown in Fig. 1. The stylus point 21 projects a substantial distance from the section 14 as shown for engagement with a record disk as will be presently described. At a point diametrically opposite the pivot 20 the section 14 is provided with a projecting supporting enlargement 23 and secured to this enlargement at 24 is a resilient centering device 25. The centering device, in the present instance, comprises a flat spring the lower end of which is provided with a guide stylus 26 adapted to engage a spiral groove 27 formed in the face of a securing nut 28.

Secured to the rear of the casing 14 is a bracket 14a and upon this bracket is a pair of spaced upstanding arms 28, between which is pivotally mounted at 30 an electric motor. This motor includes a casing 31, field coils 32, an armature 33 and a commutator 34. The armature 33 is of a length considerably less than the coils 32 and normally occupies a position shown in Fig. 2.

The armature 33 is rotatably mounted in bearings 35 of the motor by means of an armature shaft 36. The shaft 36 projects beyond the casing at one end and is reciprocably mounted in a slot 37 of a vertically extending standard 38 secured to the bracket 14a. Said standard and upstanding arms comprise a pair of mountings of which one is higher than the other to support the shaft 36 on an axial pitch. The standard 38 may include a removable cap 39 whereby the motor may be tilted to facilitate changing a record disk as hereinafter explained. In the normal or inoperative position of the motor the shaft 36 will rest on the lower end of the slot 37 as indicated in Fig. 2.

A suitable distance outwardly of the standard 38 the shaft 36 has keyed thereto at 40 a disk platen or turntable 41 of a diameter to accommodate a sound disk or record 42, and the extremity of the shaft is screw threaded as at 43 to receive the securing nut 28 for maintaining the disk securely in position upon the platen.

As has been previously stated, in normal position, the coils 32 of the motor extend beyond the inner end of the armature so that upon energization of the coil the armature 33 will be given a thrust forwardly in the direction of the centering device 25 and stylus 18 and at the same time will have the usual rotary movement. In order to permit such forward thrust the commutator 34 is of a length greater than is usually found in motors of this type so that the brushes 44 of the commutator will remain in contact therewith at all times. The record disk 42 may

be formed of any suitable material such as babbitt and the sound grooves 45 thereof are preferably formed relatively heavy in order to present a record of such durability as to withstand 5 the alternate engagement and disengagement of the stylus point 21.

The convolutions of the groove 27 formed in the face of the securing nut 28 are given an identical spacing as those of the groove 45 of 10 the record disk so that upon engagement of the stylus or pointer 26 of the centering device 25 with the groove of the nut 28 the stylus point 21 will be in direct alinement with the groove of the record disk.

15 The operation of my horn will be readily understood from the following description and reference is made particularly to Figs. 1 and 2 of the drawing.

With the parts in normal position as shown in 20 Fig. 2, when the switch 46 is closed the motor 31 will be energized by virtue of its connection with a storage battery 47. Upon energization of the motor coils 32 the armature 33 will be rotated and since the coils 32 project beyond that end of the 25 armature nearest to the record disk, the armature including its shaft 36 will be given a forward thrust due to the attraction of the armature by said coils. During such movement of the armature the nut 28 will of course be advanced so as to cause engagement of a portion 30 of the groove 27 with the point of the centering device 26. The centering device will be flexed until the stylus point 21 engages a portion of the groove 45 of the record disk and by said flexure 35 absorb the shock of engagement. It will be understood of course that as the armature is advancing as described, the platen and associated disk 42 is rotated, and as soon as the stylus 18 engages with the sound record groove, the diaphragm 16 will be given vibrations in accordance 40 with the record groove and these sounds will be emitted from the horn 19. As long as the switch 46 maintains the circuit closed to the motor the platen will continue to rotate, and as the stylus 45 18 and pointer 26 are in engagement with the respective grooves of the record disk and nut the motor 31 will be tilted upon its pivot progressively farther as the stylus rides towards the outer 50 edge of the sound disk. It will be noted that the operation of this sound disk differs from that of the ordinary sound disk in that the stylus proceeds from the inner portion of the groove to the outer portion.

As soon as the switch is opened, the field coils 55 32 will be de-energized and the armature will slide back by gravity to its normal position, the guide stylus 26 meanwhile supporting the record end of the motor due to its resiliency until the shaft 36 is retracted far enough to clear the stylus 60 on the diaphragm, when the armature is slid to the position shown in Fig. 2 in readiness for the next closing operation of the switch.

The corrugated diaphragm centralizes the pivotal movement of the guide stylus 26 for it will 65 be noted that the connection to the diaphragm is on a vertical line above the pivotal point. The corrugated diaphragm also displaces more air for

the same movement of the vibrator arm than a flat diaphragm.

From the foregoing it will be seen that I have provided a talking horn of extreme simplicity, and durable construction and while I have shown and described a preferred form of the device, it should be understood that I do not confine myself to the exact details set forth, and reserve as my own all such modifications as fairly fall within the scope of the appended claims.

10 I claim:

1. A signal comprising two styli, a diaphragm to which one stylus is attached, a support to which the other stylus is attached, a grooved record spaced from the diaphragm-styli, a turntable, 15 securing means to fasten the record on the turntable, said means having a groove matching the groove in the record, and means to simultaneously revolve the turntable and shift it toward the diaphragm and support thereby to engage the styl 20 with the grooves of the respective record and securing means.

2. A signal comprising a diaphragm having a stylus, a turntable and an attached record having a spiral sound groove, an armature-shaft assemblage carrying the turntable, a motor including field coils respecting which the armature is revolvable and shiftable, means to pivotally support the motor so that the groove will retain the stylus, supporting means for the shaft to hold the motor 30 on an incline and let the assemblage shift back from the stylus by gravity, and means to energize the field coils to revolve the assemblage and at the same time shift it forwardly until the record engages the stylus.

3. A signal comprising a casing section having a central opening and comprising a support, a bearing on said support, a diaphragm mounted on one side of the section and having a stylus extending through the opening to the other side of the section and resting on the bearing, a second stylus mounted on the support, a turntable having a record with a sound groove engageable with the diaphragm and stylus, securing means to fasten the record on the turntable having a matching groove engageable with the second stylus, an armature-shaft assemblage carrying the turntable, a motor having field coils for revolving the assemblage, said assemblage being shiftable with respect to said coils, and a mounting with respect 40 to which the motor is movable.

4. In a signal comprising a diaphragm having a stylus, a turntable, and a record and securing means by which the two are fastened together, said record being initially spaced from the stylus; an armature-shaft assemblage carrying the turntable, a motor including field coils respecting which the armature is revolvable, said armature being initially axially positioned at one side of the field coils, and a pair of mountings of which one is higher than the other to support the shaft on an axial pitch, the energization of the field coils attracting said armature toward the center of the field and causing the shaft to slip endwise up the incline as revolution begins.

65 60 65 JOSEPH E. GRIFFIN.
